United States Patent Office

Des. 180,978
Patented Sept. 10, 1957

180,978

SCREW DRIVER

Theodore R. Wagner, Denver, Colo., assignor to Todd
Tool Co., Denver, Colo., a corporation of Colorado

Application January 14, 1957, Serial No. 44,497

Term of patent 14 years

(Cl. D93—4)

Figure 1 is a side elevational view of a screw driver, showing my new design;

Figure 2 is a front elevational view; and,

Figure 3 is a fragmentary bottom plan view of the screw driver.

I claim:

The ornamental design for a screw driver, as shown.
